United States Patent Office.

HENRY L. C. MÜLLER, OF BRIDGEPORT, CONNECTICUT.

Letters Patent No. 78,888, dated June 16, 1868; antedated June 2, 1868.

IMPROVED SHOE-LACING DEVICE.

The Schedule referred to in these Letters Patent and making part of the same.

TO ALL WHOM IT MAY CONCERN:

Be it known that I, HENRY L. C. MÜLLER, of Bridgeport, in the county of Fairfield, and State of Connecticut, have invented a new and useful Improvement in Shoe-Lacing; and I do hereby declare that the following is a full, clear, and exact description thereof, which will enable others skilled in the art to make and use the same, reference being had to the accompanying drawings, forming part of this specification.

Figure 1 represents a plan or top view of my invention.

Figure 2 is a detail perspective view of the string-holder.

Figure 3 is a plan view of a modification of the same.

Similar letters of reference indicate corresponding parts.

This invention relates to a new device for fastening the upper ends of shoe-strings, and its object is to do away with the tedious process of tying the strings.

The invention consists in the use of a wire or sheet-metal hook, having two springs projecting above its sides. The string is fastened by laying it under and around the hook, and by then clamping it between the springs. It will then be firmly held, and cannot be drawn out unless its end is first released from the springs.

A A represent the two flaps of a shoe to be laced. B B are the hooks, buttons, eyelets, or other devices, around which the string C is laid, as usually. D D are the string-holders, for securing the upper ends of the strings without tying.

Each of these holders is made in shape of a hook, a, (see fig. 2,) fastened to the shoe in any suitable manner, and is provided with two springs, b b, projecting from the opposite sides of the hook, as is clearly shown in figs. 2 and 3.

These holders are either bent, from a piece of wire, into the required form, as is indicated in fig. 2, or they are made of sheet metal, stamped into the required form, as shown in fig. 3.

The string to be fastened is laid around the hook, and under the projecting part, a, of the same, and is finally clamped between the springs b b, as shown in fig. 1, when it will be securely held in place.

I claim as new, and desire to secure by Letters Patent—

A string-holder, D, for shoe-lacings, made and operating substantially as herein shown and described.

Dated at Bridgeport, the 28th day of September, 1867.

HENRY L. C. MÜLLER.
